UNITED STATES PATENT OFFICE

JOHN T. BERG, OF PEQUANNOCK, NEW JERSEY

FOLDING IRONING BOARD

Application filed May 27, 1931. Serial No. 540,303.

This invention relates to that class of ironing boards which are adapted to be folded out of the way when not in use, and the invention has particular reference to an ironing board 5 of this type which may be contained in a recess or cavity in the wall of a kitchen or other room, so that while the board may be extended beyond the wall and supported in a horizontal operative position when in use, 10 it may also be folded to an upright inoperative position and housed wholly within the recess, and the latter may if desired, be closed by a door.

The objects of the invention are to provide an ironing board of this type, which will be compact in form so as to occupy little space when folded out of use; in which provision is made for supporting the board when extended for use, in different positions of vertical adjustment; in which either end of the board may be presented for use as desired; and in which either side of the board may likewise be presented for use as desired; and in the specification to follow the invention 25 will be described in detail, and the novel features thereof will be pointed out in the appended claims.

In the accompanying drawings:

Fig. 1 is a vertical central sectional elevation of the improved ironing board structure, the ironing board being shown in extended horizontal position for use;

Fig. 2 is a similar view showing the board folded to an upright inoperative position;

Fig. 3 is a front elevation of the parts in the position shown in Fig. 1;

Fig. 4 is a horizontal sectional plan view on the line 4—4 of Fig. 3;

Fig. 5 is a horizontal section, on an enlarged scale, through one side of the board on the line 5—5 of Fig. 4, showing the form of the pivotal connection of the upper ends of the links with the ironing board;

Fig. 6 is a horizontal section on an enlarged scale on the line 6—6 of Fig. 3, showing the form of the releasable locking device for holding the board in its different positions of vertical adjustment.

Referring to the drawings:

The operative parts of the device are

mounted in and carried by a sustaining frame or casing 1, comprising a back wall 2, side walls 3, and upper and lower end walls 4, the front of the casing being closed by a door 5, as indicated in Fig. 4.

The frame or casing 1 is adapted to be fixedly secured in an upright position in a recess or cavity in the wall of the room in which the structure is to be installed, and with the ironing board folded in upright position, as will be presently described, it will be contained wholly within the casing and the door 5 thereof will close over the front of the same flush with the surface of the wall, thereby entirely concealing the board and connected parts from view.

Situated between the side walls 3 of the sustaining frame is a supporting member, in the present instance consisting of a block 7 and two legs or bars 8 depending from the ends thereof, which supporting member is adjustable up and down in guides on the frame. These guides are constituted in the present instance by the rear wall 2 of the frame and vertical beads 9 on the inner sides of the side walls near their front, between which the block 7 is guided, and by strap loops 10 projecting inwardly from the side walls of the casing near its lower end through which strap loops the bars 8 extend and are guided.

An ironing board 11 is pivotally connected at its end, in the manner to be more particularly described hereinafter, to the block 7 on a horizontal transverse axis as at 12, so that the board may be extended horizontally in operative position for use, as shown in Figs. 1, 3 and 4, or may be folded or swung upwardly to an upright inoperative position, when out of use, as shown in Fig. 2.

A retaining or safety chain 28 can be extended across the upwardly swung board as indicated in Fig. 3.

The board 11 is supported when extended in operative position, by means of two links 13 pivoted at their upper ends as at 14, in the manner described in detail later on, to the opposite side edges of the board, and pivoted at their lower ends, as at 15 to a slide or cross brace 16 formed at its ends with collars 17

loosely surrounding and movable up and down on the bars 8 of the supporting member, suitable stop devices 18 being applied to the bars in position to be engaged by the collars and thus limit the downward movement of the slide and thereby support the ironing board in horizontal position.

From the foregoing description, it will be understood that with the board extended in 10 horizontal operative position as shown in Figs. 1, 3 and 4, it will be supported by the links 13 through the medium of the slide 16 resting on the stop devices 18, and from this position the board may be folded to upright 15 inoperative position by swinging the same upwardly to the position shown in Fig. 2, in which position all of the operative parts will be wholly contained within the casing or frame 1, the slide 16 in this folding operation 20 moving upwardly on the bars 8 to its upper position as shown.

Due to the movable mounting of the supporting member 6 in the guides on the sustaining frame as described, the ironing board 25 when extended may be set at different vertical adjustments or levels in order to adapt the board for use by persons of different heights, or to enable the user to sit in a chair while using the board. To hold the board 30 in its different positions of adjustment, a locking device is provided which is carried by the bars 8, 8 and is adapted to engage at different points in the height of the side walls of the casing, so as to hold the supporting 35 member at different levels relative thereto. In the present instance this locking device is in the form of two latch bolts 19 mounted in horizontal guiding openings in the bars 8 of the supporting member, and acted on by 40 leaf springs 20 fixed to said bars and tending to project the latches outwardly to active position to engage in any one of a series of holes 21, etc., formed in the side walls 3 of the frame 1 or in strips attached to the walls, 45 as shown in Fig. 6. These latch bolts are connected together by a chain 22 which, by the pressure of the finger thereon, may be operated to retract the bolts against the force of the springs and disengage the same from 50 the holes 21; thereby freeing the supporting member and permitting the same to be moved to the desired height, after which by releasing the chain, the springs will project the locking bolts to reengage the holes.

55 The ironing board as shown in Fig. 4, is of tapering form, being wider at one end than at the other, and in the position of the parts shown in this figure, the narrower end of the board is presented for use, while the wider 60 end is connected pivotally with the supporting member as hereinbefore described. In order however, that, as occasion may demand, the wider end of the board may be presented for use, provision is made for reversing the 65 position of the board and presenting its

wider end for use, and this is effected by forming the pivotal connection of the board with the supporting member, so that this connection may be detached at will, whereupon the board may be turned around to its reverse position on the axis of the pivots of the upper ends of the supporting links. A form of pivotal connection to effect this object is best shown in Fig. 1, where it will be seen that there is fixed in each end of the board a plug 23, to each of which plugs is pivoted a plate 24 formed in its end with a hole adapted to seat over a bolt projecting upwardly from the upper side of the block 7, and having screwed thereon a thumb nut 25. With the plate confined on the bolt by the nut as shown in Fig. 1, the board is supported so that it can be swung up and down on the pivotal axis 12 of the plate with the plug. In reversing the position of the board from that shown in Fig. 1, the thumb nut is unscrewed from the bolt so as to release the plate 24, and the board is then free to be turned about the axis of the supporting links, thereby bringing the outer end of the board to position over the block 7, and the plate at that end of the board being passed over the bolt, the thumb nut is again screwed down so as to confine the plate in position as before. In this reversal of the ironing board end for end, there occurs also a reversal of the side of the board, the side of the board which before was beneath, being brought uppermost.

It may happen however, that in the use of the board the ironing surface will become marred or scorched, and in these circumstances, it may be desired to reverse the board side for side, without at the same time reversing the same end for end as just described, and to effect this object, the upper ends of the links 13 are connected to the side edges of the board in such a manner that they may be detached and thereby permit the board to be turned over. A form of connection for effecting this object is shown in detail in Fig. 5, where it will be seen that a boss 26 is fixed in each side edge of the board, which bosses project outwardly a short distance from said edges and are threaded interiorly to receive confining screws 27. The ends of the links are formed with holes to seat loosely over the bosses, and by screwing the screws into the bosses, the links will be confined thereon while, by the removal of the screws, the links may be readily detached to disengage the board. It will be understood that in this operation, it will be necessary also to disconnect the pivotal plate 24 at the inner end of the board from the bolt on the supporting member, and when the board has been turned over to its new position, this plate is again seated over the bolt and confined by the thumb screw.

It will be seen from the foregoing description and the construction illustrated,

that the ironing board may be adjusted to different vertical heights on the sustaining frame to accommodate persons of different heights, or to enable the user to sit while using the board; and it will be seen also that the ironing board may be reversed end for end so as to present either the wider or the narrower end of the board for use; and further, it will be seen that the ironing board may be turned or reversed side for side in order to prevent a new surface of the board for use when the other surface becomes marred or scorched.

In the foregoing description and accompanying drawings, the invention has been set forth in the particular detailed form and relation of the parts which have been found in practice to answer to a satisfactory degree the ends to be attained. It will be manifest however, that the construction may be changed or modified as to these details, without departing from the limits of the invention; and further, it will be understood that the invention is not limited to any particular form or construction of the parts, except in so far as such limitations are specified in the claims.

Having thus described my invention, what I claim is:—

30 1. In combination with a sustaining frame, an ironing board having a detachable horizontal pivotal connection at one end with said frame to fold to an upright inoperative position, supporting links pivoted at their upper 35 ends to the opposite edges of the board and having sliding connection at their opposite ends with the frame, means for limiting the downward movement of the links to support the board in extended operative position, 40 whereby by disconnecting the end of the board from the frame, the board may be turned end for end on the pivots of the links, and means for connecting the other end of the board in its reversed position pivotally 45 and detachably with the frame.

2. In combination with a sustaining frame, an ironing board having a detachable horizontal pivotal connection at one end with said frame to fold to an upright inoperative 50 position, supporting links pivoted detachably at their upper ends to the opposite edges of the board and having sliding connection at their opposite ends with the frame, means for limiting the downward movement of the 55 links and thereby support the board in an extended operative position, whereby by disconnecting the board from the frame and detaching the upper ends of the arms therefrom, the board may be reversed side for side, 60 and means for reconnecting the end of the board in its reversed position pivotally and detachably with the frame.

3. In combination with a sustaining frame having upright guideways, a supporting 65 member having a depending portion and

movable up and down in said guideways, means for releasably locking said member in different positions of adjustment in the guideways, an ironing board horizontal pivoted to the supporting member to fold to upright position, a couple of supporting links pivotally connected at their upper ends to the edges of the ironing board, a cross brace connected to the lower ends of the links and having sliding connection with the depending portion of the supporting member, and stops on said depending portion adapted to be engaged by said cross brace to limit the downward movement of the links and thereby support the ironing board in extended horizontal position.

In testimony whereof, this specification has been duly signed by

JOHN T. BERG.
